CLAIM

The ornamental design for an outer sonde tube timed cap, as shown and described.

DESCRIPTION

FIG. 1 is a perspective view of an outer sonde tube timed cap showing my new design;

FIG. 2 is another perspective view thereof;

FIG. 3 is another perspective view thereof;

FIG. 4 is a rear view thereof;

FIG. 5 is front view thereof;

FIG. 6 is a right-hand view thereof;

FIG. 7 is a left-hand view thereof;

FIG. 8 is a top view thereof; and,

FIG. 9 is a bottom view thereof.

The broken lines illustrate portions of the outer sonde tube timed cap that form no part of the claimed design.
